UNITED STATES PATENT OFFICE

109,520

DESIGN FOR A BOTTLE

Hilary R. Mott, Columbus, Ga., assignor to Nehi, Inc., Columbus, Ga., a corporation of Georgia

Application January 29, 1937, Serial No. 67,343

Term of patent 14 years

To all whom it may concern:

Be it known that I, Hilary R. Mott, a citizen of the United States, residing at Columbus, in the county of Muscogee and State of Georgia, have invented a new, original, and ornamental Design for a Bottle, of which the following is a specification, reference being had to the accompanying drawing, forming a part thereof;

I claim:

The ornamental design for a bottle, as shown,
HILARY R. MOTT.
